Ralph P. Patterson ^{BY} ATTORNEY

UNITED STATES PATENT OFFICE.

RALPH R. PATTERSON, OF ALAMEDA, CALIFORNIA.

REAR-VIEW MIRROR.

Application filed December 29, 1924. Serial No. 758,612.

To all whom it may concern:

Be it known that I, RALPH R. PATTERSON, a citizen of the United States, and a resident of the city of Alameda, in the county of Alameda, State of California, have invented certain new and useful Improvements in Rear-View Mirrors, of which the following is a specification.

My invention relates primarily to devices by means of which the driver of an auto vehicle, more particularly auto vehicles equipped with closed bodies, may obtain a view of the roadway at the rear of his own vehicle, and the object thereof is to provide a cheap, simple and efficient device for this purpose which may be positioned for use without any alteration in the vehicle body and which may be easily and quickly secured in its place of use.

Other objects and advantages will appear hereinafter and, while I have shown and will describe the preferred form of my invention, I wish it understood that I do not limit myself to such preferred form, but that various changes and adaptations may be made therein without departing from the spirit of my invention.

In the drawings accompanying and forming a part hereof:

Fig. 1 is a fragmentary perspective view of a vehicle equipped with a closed body showing my device positioned for use.

Fig. 2 is a perspective view of my device detached from its place of use.

Fig. 3 is a section on the line 3—3 of Fig. 2, also showing the method of securing my device in position for use.

Referring to the drawings, 5 indicates the front door of a closed vehicle body, 6 the window opening therein, and 7 the glass forming the window, which is shown in its lowered position within the recess formed within the door for its reception.

My device comprises a strip of glass 8, the rear side of which is silvered to form a mirror. Strip 8 is provided with holes 9 and 10, one at each end thereof through which are passed the screws 11. Washers 12 are mounted on the outer side of strip 8 and receive the head of the screws 11.

In positioning my device I prefer to remove the usual window stop at the front side of the window and substitute therefor

my glass member 8, the apertures 9 and 10 therein being positioned to register with the screw holes into which the screws originally securing the stop in position projected, thereby avoiding the necessity for drilling new holes in the body of the vehicle and rendering my device easy and simple to position for use.

In substituting my device for the usual window stop, not shown, the screws 11, which originally held the usual stop positioned at each end, are passed through the washers 12 and the apertures 9 and 10 and are then, by means of a screw driver, tightened, and the device is ready for use. The position of the mirror, relative to the car-body, adapts it to reflect images of objects located rearwardly and received along the side of the body of the car. In descending from the car the driver may, by looking into my device, have a view of the traffic approaching from the rear at all times. Due to the fact that the device is positioned substantially parallel with the windshield, he may when driving observe traffic approaching from the rear without removing his attention from the road ahead, thereby avoiding any possibility of accident.

Having described my invention, what I claim is:

1. The combination with a vehicle-body and a window thereof, of a rear view mirror comprising a strip of reflective material mounted within said window and constituting a stop therefor.

2. The combination with a closed vehicle-body and a window thereof, of a rear view mirror comprising a strip of reflective material mounted within said window, adjacent the windshield, and constituting one of the stops therefor and so positioned as to reflect images of objects located rearwardly and received along the side of the vehicle in a direction permitting said images to be viewed by said vehicle's driver.

3. The combination with a closed vehicle-body and a window thereof, of a rear view mirror comprising a strip of reflective material mounted within the window-opening adjacent to and substantially parallel with the windshield of said vehicle, as and for the purpose specified.

4. The combination with a closed vehicle-

body and a window and window-frame to reflect images of rearwardly approaching traffic rearwardly, of a rear view mirror comprising a strip of reflective material mounted within the window-frame adjacent the windshield of said vehicle and constituting one of the stops for the guidance of said window, in raising and lowering, and so positioned as

In witness that I claim the foregoing, I ¹⁰ have hereunto set my hand this 23rd day of December, 1924.

RALPH R. PATTERSON.
